UNITED STATES PATENT OFFICE.

LOUIS SPIRUP, OF AUDUBON, IOWA.

DESIGN FOR A BREASTPIN.

42,250.

Specification for Design.

Patented Feb. 27, 1912.

Application filed September 5, 1911. Serial No. 647,782. Term of patent 7 years.

To all whom it may concern:

Be it known that I, LOUIS SPIRUP, a citizen of the United States, residing at Audubon, in the county of Audubon and State of Iowa, have invented a new, original, and ornamental Design for Breastpins, of which the following is a specification, reference being had to the accompanying drawing, forming part thereof.

The figure is a plan view of a breastpin, showing my new design.

I claim:

The ornamental design for a breastpin, as shown.

Des Moines, Iowa, August 1, 1911.

LOUIS SPIRUP.
